[57] CLAIM

The ornamental design for an icicle light support clip, as shown and described.

DESCRIPTION

FIG. 1 is a top front perspective view of a icicle light support clip, showing our design;
FIG. 2 is a top plan view thereof;
FIG. 3 is a left side elevation view thereof;
FIG. 4 is a front elevational view thereof, the rear being a mirror image;
FIG. 5 is a right side elevation view thereof; and,
FIG. 6 is a bottom plan view thereof.
